GEM SETTING OR SIMILAR ARTICLE

Rubin Rosenthal, New York, N. Y.

Application October 21, 1949, Serial No. 5,611

Term of patent 3½ years

(Cl. D45—1)

To all whom it may concern:

Be it known that I, Rubin Rosenthal, a citizen of the United States, and a resident of New York, New York, whose postoffice address is 126 West 46th Street, New York, N. Y., have invented a new, original, and ornamental Design for a Gem Setting or Similar Article, of which the following is a specification, reference being had to the accompanying drawing, forming a part thereof, in which

I claim:

The ornamental design for a gem setting or similar article, as shown.

RUBIN ROSENTHAL.
